UNITED STATES PATENT OFFICE.

JAMES B. KIRBY, OF CLEVELAND, OHIO, ASSIGNOR TO ELECTRIC VACUUM CLEANER COMPANY, INC., A CORPORATION OF NEW YORK.

BRUSH AND METHOD OF MAKING SAME.

1,333,663.

Specification of Letters Patent. Patented Mar. 16, 1920.

Application filed April 4, 1916. Serial No. 88,759.

To all whom it may concern:

Be it known that I, JAMES B. KIRBY, a citizen of the United States, residing at Cleveland, in the county of Cuyahoga and 5 State of Ohio, have invented a certain new and useful Improvement in Brushes and Methods of Making Same, of which the following is a full, clear, and exact description, reference being had to the accompanying 10 drawings.

This invention relates to brushes and especially to the elongated, cylindrical or helical form of brush much used in various machinery such a suction-cleaners, carpet 15 sweepers, currying machines, and the like. The objects of the invention are the provision of a brush in which the bristles are secured against any possibility of being pulled out; which shall keep itself clean; 20 and which shall be peculiarly cheap in construction.

The invention in both its aspects, is defined in the claims hereto annexed and illustrated in the drawings accompanying and 25 forming part of this application wherein: Figures 1, 2, 3, 4 and 5 illustrate successive steps in the manufacture of my improved brush; Fig. 6 is a perspective view of the device as it appears after the fifth operation; Fig. 7 is a perspective view of the brush after the sixth operation of twisting 30 has been completed; and Fig. 8 is a perspective view of the twisted brush rod, the bristles being omitted.

35 Describing the parts by reference characters 1 and 2 represent the die members for holding and manipulating the parts of my improved brush. In the present embodiment I have shown them as connected by a 40 screw 3, thus forming a sort of vise, though these die members can, if desired be supported and manipulated by some other mechanical means. One of these members is provided at its face adjacent the other member 45 with a recess 4 opening through its top, and adapted to receive the brush blank which consists of an S shaped strip of thin metal such as sheet iron.

The cross section of this blank is shown 50 in Fig. 1 from which it will be seen that each convolution of the S has a flaring opening, then a slight constriction, and then a larger cavity. The length of the blank is the same as the length of the brush desired, and the 55 dies 1, 2, are at least as long as this blank.

The blank 5 having been secured in the recess as shown, a suitable supply of bristles 6 of the desired length is applied to the top thereof so as to project transversely thereof with their middles over the upwardly opening channel. Any suitable method of distributing and evening these bristles may be employed, it being immaterial to the present invention whether this be done by hand or by some mechanical means. A rod 65 or wire 7 is then laid upon these bristles in register with the open channel and forced down into that channel by operating the plunger 8, whereupon the parts assume the condition shown in Fig. 2. The length of 70 the rod or wire 7 is at least as great as that of the blank 5 (see Fig. 6), and the constriction of the channel is such as to hold the bristles and rod therein after the plunger is removed.

The blank is then reversed to the position shown in Fig. 3, a new supply of bristles 6a applied, a second rod or wire 7a provided, and the plunger 8 actuated a second time, thus producing the condition shown in Fig. 4. The plunger is then removed and lateral pressure applied to the sides of the blank so as to close the channels and pinch the bristles tightly together and about the rods or wires. I have illustrated these manipulations as all performed by the same dies or jaws though it is obvious that different jaws of the same or different shapes could be employed. The protruding ends of the bristles are then sheared or trimmed whereupon the 90 device appears as shown in Fig. 6.

The whole brush is then twisted, preferably by holding one end and rotating the other, since the uniform stiffness of the brush will result in a uniform twist. The 95 brush is then complete except for the application of end caps, fittings, wheels, bearings or the like (not shown) which may be of any construction or secured in any of the numerous ways known to the art.

10 While I have described my invention in detail I do not confine myself to such details, either of construction or manipulation, except as the same may be positively recited in the claims hereto annexed or may be rendered necessary by the prior state of the art.

Having thus described my invention, what I claim is:—

11 1. In a brush, a one piece sheet metal base

member folded to produce a pair of longitudinal channels which open in different directions, said channels having a common wall, a rod or wire in each channel, and 5 bristles projecting from each channel, the mid portions of said bristles being bent around said rods or wires.

2. In a brush, a bendable metal member having a longitudinal channel and a rod or 10 wire in said channel, bristles bent around said rod or wire and having their ends projecting from said channel, and said channeled member being twisted from end to end so that said bristles define helical convolutions.

15 3. In a brush, a base member having a pair of longitudinal channels which open in different directions, a rod or wire in each channel, and bristles projecting from each

channel, the mid portions of said bristles 20 being bent around said rods or wires, said base member being twisted from end to end so that said bristles define helical convolutions.

4. In a brush, a one piece sheet metal 25 base member folded to produce a pair of longitudinal channels having a common wall, and bristles held in each channel and projecting in opposite directions.

5. In a brush, a one piece sheet metal 30 member folded to produce a pair of longitudinal channels having a common wall, and bristles held in each channel, said member being twisted longitudinally about an axis within itself.

35 In testimony whereof, I hereunto affix my signature.

JAMES B. KIRBY.
